UNITED STATES PATENT OFFICE.

ANDREW F. CURTIN, OF MEDFORD, MASSACHUSETTS.

BALL-COCK.

1,179,507.

Specification of Letters Patent. Patented Apr. 18, 1916.

Application filed April 23, 1915. Serial No. 23,328.

To all whom it may concern:

Be it known that I, ANDREW F. CURTIN, a citizen of the United States, residing at Medford, in the county of Middlesex and State of Massachusetts, have invented certain new and useful Improvements in Ball-Cocks; and I do hereby declare the following to be a full, clear, and exact description of the invention, such as will enable others skilled in the art to which it appertains to make and use the same.

The present invention relates to an improvement in ball-cocks, and more particularly, to an improvement in ball-cocks provided with a water passage surrounding the valve and connecting the inlet and the outlet of such formation that the flow of water therethrough is retarded. In the use of ball-cocks provided with water passages of this description, if the pressure of the water flowing through them drops below a certain point, the tanks supplied by them are filled too slowly.

The object of the present invention is to produce a retarding water passage ball-cock having an auxiliary water passage or by-pass connecting the inlet and the outlet and provided with a controlling valve by which the volume of water passing therethrough may be regulated.

To this end the invention consists in the improved ball-cock hereinafter described and particularly pointed out in the claims.

In the accompanying drawings illustrating the preferred form of the invention, the ball-cock comprises a valve-shell or body in which is received a longitudinally movable valve 2 controlled by the float. The upward pressure of the float causes the valve to be seated against the valve-seat 3 formed on one end of a removable member 4 held in position by an inlet tube 5 coupled to the lower end of the valve-body by a coupling-nut 6. The flow of the water from the inlet 7 formed in the member 4 to the outlet 8 is through a circuitous or spiral passage 9 which has a retarding effect upon the water; the retardation of the flow of the water being utilized to cause sudden closing of the valve thereby eliminating the hissing sound accompanying a slow closing of the valve. The ball-cock thus far described forms the subject-matter of Letters Patent No. 829,462 issued to me August 28, 1906. In addition to this circuitous spiral or retarding water passage 9 which constitutes the main water

passage the improved ball-cock is provided with an auxiliary, free-flowing water passage or by-pass 10, located in the valve-shell or body 1 and separated from the circuitous passage by the inner wall 11. One end of the by-pass gives into an inlet chamber 12 surrounding the valve-seat 3. This chamber receives the stream of water from the inlet before it passes into the circuitous passage 9. The other end of the by-pass gives into the outlet chamber 13 into which the circuitous passage discharges and which in turn discharges through the outlet 8. A screw valve 14 is received in the discharge end of the by-pass and seats itself at 15 just below the discharge chamber 13. When the stream of water flowing through the passage 9 is under sufficient pressure to fill the tank within the desired period, the valve 14 is screwed down on its seat 15. Where, however, the water pressure falls below the required degree, the valve 14 is unscrewed to an extent sufficient to permit the necessary additional quantity of water to pass out through the outlet chamber 13 and the outlet 8 to fill the tank within the required time. Under normal conditions of use, that is to say, when the water is under normal pressure, the valve 14 is permitted to remain seated, and the stream of water, when the valve 2 is unseated, flows only through the circuitous or spiral passageway 9 on its passage from the inlet 7 to the outlet 8. But under abnormal conditions, that is to say, in places where the water pressure falls below normal, the valve 14 is unscrewed until the volume of water flowing through the opening thereby made between the passage 10 and the outlet chamber 13 is large enough together with the water flowing through the circuitous passage-way 9 to fill the tank within the required time.

The present invention contemplates a ball-cock provided with a main retarding water passage from the inlet to the outlet and an auxiliary water passage or by-pass from the inlet to the outlet, this latter passage being closed during normal water pressure conditions of operation of the ball-cock. The auxiliary passage is provided with means by which, when conditions make it necessary to use the passage, the volume of water flowing through the passage from the inlet to the outlet may be properly regulated. It is to be observed that with higher pressures the auxiliary passage is

closed, but with the lower pressure it is opened more or less. The invention may, therefore, be embodied in other forms than that described above.

5. Having thus described my invention, what I claim is:
1. A ball-cock having in combination, a valve-body having an inlet and an outlet, a main retarding flow passage connecting the inlet and the outlet, a valve-seat located in the inlet, a valve movable longitudinally in the valve-body and adapted to press against the valve-seat for controlling the flow of water through the inlet, and an auxiliary 10 or free-flow by-pass passage connecting the inlet and the outlet having provision permitting a portion of the water passing through the inlet to flow through the by-pass.
  15. 2. A ball-cock having in combination, a valve-body having an inlet and an outlet, a main retarding flow passage connecting the inlet and the outlet, a valve movable in the valve-body for controlling the flow of water 20 through the passage and an auxiliary or free-flow by-pass passage connecting the in-

let and the outlet having a valve for regulating the flow of water through the by-pass operating when opened wider with decreased water pressure to shorten the valve 30 operating time.

3. A ball-cock having in combination, a valve-body having an inlet and an outlet, a main retarding flow passage connecting the inlet and the outlet, an auxiliary or free-flow 35 by-pass passage connecting the inlet and the outlet, and means for regulating the proportionate amounts of water flowing through the retarding and the free flowing passages.

4. A ball-cock having, in combination, a valve body having an inlet and an outlet, a main passage from the inlet to the outlet having provision for retarding the flow of water therethrough, an auxiliary passage 45 from the inlet to the outlet having provision for free flow of water therethrough, a valve seat located in the inlet, a valve for opening and closing the inlet affording simultaneous flow of water to both passages. 50

ANDREW F. CURTIN.
